UNITED STATES PATENT OFFICE.

ERICK WALDEMAR LINDGREN, OF HAGALUND, NEAR STOCKHOLM,
SWEDEN.

COIN-CONTROLLED LIQUID-VENDING APPARATUS.

No. 817,788.

Specification of Letters Patent.

Patented April 17, 1906.

Application filed September 19, 1904. Serial No. 225,113.

To all whom it may concern:

Be it known that I, ERICK WALDEMAR LINDGREN, engineer, a subject of the King of Sweden and Norway, residing at Hagalund, near Stockholm, Sweden, (whose post - office address is Järfvagatan 6, Hagalund, near Stockholm, Sweden,) have invented certain new and useful Improvements in Coin-Controlled Liquid-Vending Apparatus; and I do declare the following to be a full, clear, and exact description of the invention, such as will enable others skilled in the art to which it appertains to make and use the same.

My invention relates to improvements in coin-controlled liquid-vending apparatus and will be fully described and pointed out in the following specification, claims, and drawings.

In the drawings, Figure 1 is a view in side elevation, with parts in section, of a vending apparatus embodying the main features of my invention. Fig. 2 is a plan view of the parts shown in Fig. 1.

Like characters of reference designate similar parts throughout the different figures of the drawings.

The general object of my invention is to provide a vending apparatus in which the use of springs is entirely avoided, the operative parts thereof being actuated entirely by gravity.

A further object of the invention is to provide efficient means for quickly and effectively opening and closing the valves which control the passage of the vended fluid and also means for regulating the amount of fluid to be sold and the denomination of coins to be used.

The device of my invention consists generally of a coin mechanism operating in connection with a weighted measuring-cup actuated by a weight which upon the insertion of a coin of the proper denomination serves to raise the measuring-cup adjacent a valved filling-pipe, actuating the valve therein and permitting the cup to descend to an emptying position when the same has received a prescribed quantity of the liquid. When the measuring-cup has reached the emptying position, the contents thereof is automatically drained, and the same is adapted to be locked and to remain in the emptying position until another coin is inserted.

My invention consists more particularly in a measuring-cup 3, mounted upon a weighted

lever 1, having bifurcated arms 2, to which the cup 3 is directly attached. Said lever 1 is also provided with a weight-rod 4, extending in an opposite direction to the arms 2 and carrying on its outer end a weight 5, adjustably secured by means of a screw 5^a. The said weight is adjusted upon the rod in a manner to normally hold the cup in a filling or elevated position, as indicated in Fig. 1 in dotted lines, the said cup overbalancing the weight upon the admission thereto of a prescribed quantity of the liquid. The weight-rod 4 carries a detent-rod 8, adapted to be engaged by a detent 7, formed upon a pivotally-mounted coin-controlled lever 6. Said lever 6 is provided with a rod carrying a weight 17, which is adjustably mounted. The lever 6 is also provided with a coin-pocket 9, adapted to register with the delivering end 20 of a coin - chute 19, said coin - pocket 9 being equipped with a closable outlet, the closure thereof consisting of a weighted coin-flap 18, pivotally mounted on the lever 6 and adapted to be engaged by a flap-lug 21, formed on one of the arms 2. The lower end of said measuring-cup 3 is provided with an automatic valve provided with a winged closure 15, adapted to be opened by engagement with a lug formed in an outlet-pipe 16.

The filling mechanism consists of a filling-pipe 12, projecting within the measuring-cup 3 at one end and terminating at the other end in a valve-casing 12^a. The valve-casing communicates with a source of supply through the medium of a supply-pipe 10, said casing being provided with a central diaphragm having a valve-seat which is opened and closed by a closure 11, provided with a projecting stem 13. Said stem 13 projects downwardly from the casing through a packing-box or gland and registers with a stem-actuating lever or lift 14, pivoted at one end upon a stationary part of the device and normally engaging at its other end a projecting stud 22. Provision is made whereby upward movement of the measuring-cup 3 and valve-stem 13 is arrested at a prescribed point, which means consists, as shown, of a projecting rest-arm 23, engaged by the weight 5, as shown in dotted lines in Fig. 1.

The operation of the device is as follows: When a coin is inserted in the chute 19, the same is deposited in the pocket 9, carrying the outer end of the lever 6 downwardly and

disengaging the detent 7 from the detent-rod 8. It will be understood that the weight 17 will be so adjusted as to prevent disengagement of the detent 7 and rod 8 when a coin less than the prescribed denomination in payment for the liquid has been deposited. Assuming that the proper coin has been deposited, the disengagement of the detent 7 with the rod 8 will permit the weight 5 to travel downwardly, carrying the cup 3 into the elevated position shown in dotted lines. During the upward movement of the cup the lug 21 engages the cutter or weighted end of the coin-flap 18, serving to release the coin from the pocket 9, whereupon it may be received in any suitable coin-receiver. One of the arms 2 in its upward movement by means of lug 22 raises the stem-lift 14, thereby opening the valve-closure 11 and permitting the fluid to flow downwardly from the supply-pipe 10 through the casing 12^a and filling-pipe 12 into the measuring-cup 3. When the prescribed quantity of fluid has been deposited into the measuring-cup, or, in other words, when the measuring-cup overbalances the weight 5, it will begin to descend accompanied by the valve-closure 11, which is permitted to close by the descending lug 22 and lift 14. When the cup reaches the position shown in full lines in Fig. 1, the valve 11 will have been closed and the stem of the wing-valve 15, engaging the lug formed in the outlet-pipe 16, will have opened the lower end of the cup 3, permitting the liquid to flow outwardly and be delivered to the purchaser. When the cup 3 has descended to a lowermost or emptying position, the detent-rod 8 will be engaged by the detent 7, the coin-flap 18 will automatically close the pocket 9, thereby placing the parts in a position to be operated upon the insertion of a coin by the next purchaser.

The operation and general construction of the device of my invention is very simple and the operative parts are wholly composed of gravity-acting mechanical elements, thus insuring both accuracy and durability. The means for regulating the amount of liquid to be sold, together with the means for determining the denomination of the coins to be used, are both simple and sensitive in their operation and capable of accurate adjustment.

While I have herein shown and described a specific embodiment of my invention, I do not wish to be limited to the precise construction shown, as it is obvious that changes may be readily made thereto without departing from the spirit of the invention.

Therefore, what I claim, and desire to secure by Letters Patent, is—

1. A liquid-dispensing apparatus comprising a supporting structure, a measuring-cup, a cup-supporting lever pivotally secured thereto at one end and provided at its opposite end with an adjustably-mounted weight, a stop limiting the movement of said weight in one direction, a lug mounted on the weighted end of said lever, a coin-controlled lever provided with a projecting pawl adapted to engage said lug, a weight normally holding said lever in a position to engage the pawl with said lug, the opposite end of said lever having a coin-receiving pocket adapted to receive coins of a prescribed denomination, the weight of said coins serving to disengage said pawl and lug, a filling-pipe for said cup, a valve in said pipe having a projecting stem, a pivotally-mounted valve-lever adapted to engage said stem and located in operative relation to said cup-supporting lever, a self-closing valve secured in the lower end of the measuring-cup having a stem projecting below the same, and a receiving or draining pipe serving to open said valve. 85

2. A liquid-dispensing apparatus comprising a structure, a measuring-cup, a cup-supporting lever pivotally secured thereto at one end and provided at its opposite end with an adjustably-mounted weight, a stop limiting the movement of said weight in one direction, a lug mounted on the weighted end of said lever, a coin-controlled lever provided with a projecting pawl adapted to engage said lug, a weight normally holding said coin-lever in a position to engage the pawl with the lug, the opposite end of said lever having a coin-receiving pocket adapted to receive coins of a prescribed denomination, the weight of said coins serving to disengage said pawl and lug, a weighted pocket-lever pivotally mounted to said coin-lever and serving normally to hold the coin in said pocket, said pocket-lever releasing the coin from said pocket when the pawl and lug are disengaged, a filling-pipe for said cup, a valve in said pipe having a downwardly-projecting stem, a pivotally-mounted valve-lever adapted to engage said stem and located in operative relation to said cup-supporting lever, a self-closing valve secured in the lower end of said measuring-cup having a stem projecting below the same, and a receiving or draining pipe provided with a lug adapted to engage said valve-stem. 115

In testimony whereof I affix my signature in presence of two witnesses.

ERICK WALDEMAR LINDGREN.
